Primary Examiner—M. N. Pandozzi*Attorney, Agent, or Firm*—Wolf, Greenfield & Sacks, P.C.[57] **CLAIM**

The ornamental design for a combination cake server, salad bowl, and dip tray, as shown and described.

DESCRIPTION

FIG. 1 is a perspective view of the combination cake server, salad bowl, and dip tray according to our new design, the top being transparent;

FIG. 2 is a bottom plan view thereof;

FIG. 3 is a top plan view thereof;

FIG. 4 is a side elevational view thereof, as seen from the right side of FIG. 3, the left side elevational view being a mirror image thereof;

FIG. 5 is a side elevational view rotated 45° from the view of FIG. 4, the opposite side being a mirror image thereof;

FIG. 6 is an exploded, top, perspective view thereof; and,

FIG. 7 is an exploded, bottom, perspective view thereof.
